A. B. Corby

United States Patent Office.

ALPHEUS B. CORBY, OF BINGHAMTON, NEW YORK.

Letters Patent No. 77,462, dated May 5, 1868.

IMPROVEMENT IN CHURNS.

The Schedule referred to in these Letters Patent and making part of the same.

TO ALL WHOM IT MAY CONCERN:

Be it known that I, ALPHEUS B. CORBY, of Binghamton, in the county of Broome, in the State of New York, have invented certain new and useful Improvements in the Mechanism used for the Purpose of Propelling or Operating Churns; and I do hereby declare that the following is a full, clear, and exact description of the construction and operation of the same, reference being had to the accompanying drawings, making a part of this specification, in which—

Figure 1 is a side elevation.

Figure 2, an end elevation.

Figures 3, 4, 5, and 6, separate views of the various parts.

Similar letters refer to corresponding parts in the several figures.

This invention relates to that class of churn-powers which are operated by a weight attached to clock-work machinery, and consists of the various devices hereinafter described.

For the purpose of supporting the mechanism employed, I construct the frame, A B C D, of cast iron or other suitable material, and place it upon the platform or floor O of the stout wooden frame a b c d.

Between the sides A B, and supported by them, I place a strong drum, R, with journals on each end, which work in the sides A B, and allow it to turn freely on its axis. The drum R carries the spur-wheels W W', the latter moving freely on the axis of the drum, except when held by the ratchet-wheel t, which is permanently attached to the axis of the drum.

In winding the weight-rope around the drum, the spur-wheel W is held stationary, by the pawl p and spring s. The spur-wheel W' is permanently attached to the axis of the drum R, and turns the drum, when operated by the pinion i and handle k. The pinion i is adjustable, so as to be thrown out of mesh, as shown by dotted lines, while the operation of churning is going on.

The weight-rope is carried up over a pulley at the upper end of the post a. As the weight, T, descends, it turns the spur-wheel W, which operates the pallets v v', forming, in connection with the shafts g G and cam F, an escapement-apparatus, which regulates the motion of the pendulum P. To the pendulum-rod may be attached the connecting-bar, k, for a rotary or oscillating-dasher, or a working-beam, as shown by dotted lines for vertical dashers.

In the escapement-apparatus, of which an enlarged view is given in fig. 6, the pallets are made with one heavy end, so as to raise the point as it is released from the cogs of the spur-wheel. To keep the point from rising too high, and to guide it back to the cogs again, I provide the guide-pieces, m and n, pivoted to the frame A, and held in place by the springs r r'. To prevent the guide n from dropping too low, the pin y is inserted, and to guide both the pallets v v', the pins e e are inserted near the points.

The weight T may be increased or diminished, to adapt the power to the amount of cream or milk to be churned.

The speed of the operation may also be regulated by altering the length of the working-beam, or moving the end of the connecting-bar, k, up or down on the shaft of the dasher.

Having thus described the construction and operation of my improvement, what I claim as my invention, and desire to secure by Letters Patent, is—

1. The escapement-apparatus, consisting of the pallets v v', cam F, shafts g G, and guides m n, when used for the purposes described.

2. The arrangement and combination of said escapement-apparatus with the spur-wheels W W', drum R, ratchet-wheel t, pinion i, weight T, pendulum P, and frame A B C D, substantially as and for the purpose set forth.

A. B. CORBY.
